FLYING TOY

Curtis A. Anderson, Larchmont, N. Y.

Application May 12, 1950, Serial No. 9,907

Term of patent 3½ years

(Cl. D34—15)

To all whom it may concern:

Be it known that I, Curtis A. Anderson, a citizen of the United States of America, residing at Larchmont, New York, in the county of Westchester and State of New York, have invented a new, original, and ornamental Design for a Flying Toy, of which the following is a specification, reference being had to the accompanying drawing, forming part thereof.

In the drawing:

Fig. 1 is a top plan view of a flying toy showing my new design;

Fig. 2 is a side view; and

Fig. 3 is a front view.

I claim:

The ornamental design for a flying toy, substantially as shown.

CURTIS A. ANDERSON.
